[57] **CLAIM**

The ornamental design for an extruded section, as shown and described.

DESCRIPTION

FIG. 1 is an end elevational view of one end of an extruded section showing my new design, the opposed end being a mirror image of the one end; and,

FIG. 2 is a perspective view thereof from one end, the bottom and one side, the opposed side being a mirror image of the one side, with the extruded section shown broken away to disclose indefinite length.
